UNITED STATES PATENT OFFICE

137,784

DESIGN FOR A BACK COMB

Robert Lester Motley, Dayton, Ohio

Application December 30, 1943, Serial No. 112,127

Term of patent 14 years

(Cl. D86—8)

To all whom it may concern:

Be it known that I, Robert L. Motley, a citizen of the United States of America, residing at Dayton, county of Montgomery, and State of Ohio, have invented a new, original, and ornamental Design for a Back Comb, of which the following is a specification reference being had to the accompanying drawing, forming a part thereof, wherein:

I claim:

The ornamental design for a back comb, as shown.

ROBERT LESTER MOTLEY.
